UNITED STATES PATENT OFFICE.

MELVIN OVESTRUD, OF STILLWATER, MINNESOTA, ASSIGNOR TO TWIN CITY FORGE & FOUNDRY COMPANY, OF STILLWATER, MINNESOTA, A CORPORATION OF MINNESOTA.

FURNACE FOR HEATING TIE-PLATE FLANGES.

Application filed April 29, 1925. Serial No. 26,672.

My invention relates to improvements in furnaces adapted particularly for heating tie-plate flanges.

In one method for forming tie-plates of the character disclosed in Letters Patent of the United States, No. 1,171,581, Feb. 16, 1916, to Edmund H. Barrett, a long steel blank, comprising a body plate formed with a flange longitudinally thereof and perpendicular thereto, is punched in transverse zones thereof to form spike holes, said zones being severed from the blank to provide tie-plate sections. The flanges on these tie-plate sections are then heated and bent to form jaw members, each tie-plate thus formed including a platform perforated to receive anchoring spikes and also including a jaw member on said platform for engaging the upper surface of a rail base. Since the flange of a severed and punched tie-plate section is the only part thereof that is bent, it is unnecessary to heat for bending any portion of such tie-plate section other than said flange.

An object of the present invention is to provide means adapted to adequately heat for bending the flanges of a multiplicity of such tie-plate sections, said means being adapted to avoid the wasteful use of fuel by confining the heat generated therefrom particularly to the flanges of said tie-plate sections.

Another object of the invention is to provide a furnace designed to slidably receive a movable train of tie-plate sections, one abutting another edge to edge, said furnace being adapted to heat the flanges on the tie-plate sections in the travel of said tie-plate sections therethrough and to direct said sections, in such travel, from one machine to another machine employed in the process of forming a tie-plate from a blank.

A further object of the invention is to provide a furnace, as above noted, the bodies of the tie-plate sections introduced thereto forming a traveling closure for an opening in the furnace structure provided to receive the flanges on said bodies.

An additional object of the invention is to supply, in connection with a furnace of the instant nature, means for advancing a train of tie-plate sections through said furnace, said means providing for the conven-

ient feeding of new sections to a train in the progress through the furnace.

With the foregoing and other objects in view, which will appear in the following description, the invention resides in the novel combination and arrangement of parts and in the details of construction hereinafter described and claimed.

In the drawings, Fig. 1 is a side elevational view of a furnace embodying my invention; Fig. 2 is a plan view thereof; Fig. 3 is a transverse sectional view of the same, said view being taken on the line 3-3 of Fig. 2; Fig. 4 is a longitudinal sectional view taken on the line 4-4 of Fig. 2 and Fig. 5 is a perspective view of a tie-plate section of the type which said furnace is particularly designed to accommodate.

Referring to the drawings, it will be observed that the illustrated embodiment of my invention includes a furnace body 10 constructed from fire brick or other refractory material to form two elongated combustion chambers A, said body being reinforced with bottom and side plates 11, 12. Each chamber A, vaulted at the ceiling thereof, opens at its upper portion through a slot 13 formed in the top of the furnace body 10, the extremities of said slot opening through the ends of said body 10. Hung in openings 14 in the sides and in one end of the furnace body 10 are nozzles 15, one side nozzle and one end nozzle being provided for each chamber 10. These nozzles 15 communicate through tubes 16 with a source of air supply under pressure, each nozzle being fitted with a fuel inlet nipple 17 connected with a valved feed pipe 18 for liquid fuel. Said air blast nozzles 15 are of customary design and, fed with oil through the nipples 17 in the usual manner, they provide for the introduction of a readily combustible mixture to the chambers A. On top of the furnace body 10 are two pairs of rail plates 19, 20, one pair for each slot 13. These rail plates 19, 20 cover the upper margins of their respective slots 13, the corresponding ends of said plates being extended considerably beyond one end of the body 10 of the furnace. Guide bars 21, 22 respectively secured to the rail plates 19, 20 on the upper sides thereof and in parallelism therewith

are braced one with respect to the other by

means of tie-beams 23 traversing said guide bars 21, 22 and bolted thereto with bolts 24. Hung from the tie-beams 23 and between each pair of guide bars 21, 22 is a keeper bar 25.

At the end of the furnace body over-reached by the rail plates 19, 20 is a tie-plate pushing device B, which includes a rock-shaft 26 supported in brackets 27 anchored to said end of said furnace body. A lever 28 fixed to said rock-shaft 26 is connected through a link 29 with a crank 30 on a crank-shaft 31 journaled in a bracket 32 anchored to the body 10 of the furnace. Said crank shaft 31 has a belt pulley 33 fixed thereto and to which power is applied for driving said pushing device B. Rising from the rock-shaft 26 are a pair of spaced arms 34. One arm 34 is connected through a link 35 with a pusher head 36 slidably resting on one pair of rail plates 19, 20 and between the guide bars 21, 22 on said plates. The other arm 34 is connected through a link 35 with a pusher head 36 slidably resting on the other pair of rail plates 19, 20 and between the guide bars 21, 22 thereon. Rotation of the pulley 33, results in the synchronous reciprocation of the pusher heads 36 on the rail plates 19, 20. The throw of said pusher heads 36 is slightly greater than the width of a tie-plate section for which the furnace is designed. Such tie-plate section is shown in Fig. 5 and it consists of a platform 37, punched as at 38 to receive spikes, said platform having a flange 39 traversing the same. Tie-plate sections of this kind are struck from blanks in one press and then resolved into completed tie-plates by having the flanges thereof bent in another press to form jaw members. The instant furnace heats for bending, the flanges of such tie-plate sections, the heating operation being effected by confining the furnace heat particularly to said flanges and during the conveying by said furnace of the tie-plate sections from one press to the other.

In using the device, tie-plate sections are laid, flanges down, on the rail plates 19, 20 in front of the retracted pusher heads 36 at the ends of the return strokes of said heads. The continuance of this operation maintains a train of tie-plate sections on each of the pairs of rail plates 19, 20, each train moving a step upon each working thrust of its respective pusher head 36. Being diminished by one tie-plate section, as the leading section is ejected from the furnace upon the working throw of its respective pusher head 36, each train of sections is replenished with a new one after said pusher head 36 has been retracted. The flanges of the tie-plate sections, due to the appropriate timing of the plunger heads 36, are properly heated for bending after they have traveled the length of the furnace and as they are ejected or

taken therefrom at the delivery ends of the rail plates 19, 20. In the travel of the tie-plate sections over the rail plates 19, 20, the guide bars 21, 22, co-operate with the ends of said sections and keep them, laterally, in train-like formation with the flanges thereof amply clearing the sides of the slots 13. In such travel, said sections, spanned by the keeper bars 25, are held by said bars against buckling upwardly under the thrusts imparted thereto by the pusher heads 36. The slots 13 are only sufficiently wide to freely receive the flanges of the tie-plate sections. This provision conserves in heat units as it practically confines the heat of the burning fuel to the flanges of the tie-plate sections.

Changes in the specific form of my invention, as herein disclosed, may be made within the scope of what is claimed without departing from the spirit of my invention.

Having described my invention, what I claim as new and desire to protect by Letters Patent is:

1. A furnace for heating the flanges of tie-plate sections comprising a body portion having a heated chamber and an elongated slot communicating with said chamber, guideways formed along said slot for the reception of a series of flanged tie-plates, said slot being adapted freely to receive the flanges of such tie-plates, and means for progressively moving said tie-plates along said guideways.

2. A furnace for heating the flanges of tie-plate sections comprising a body portion having a heated chamber and formed with an elongated slot communicating with said chamber, guideways formed along said slot for the reception of a series of flanged tie-plates, said slot being adapted freely to receive the flanges of such tie-plates, means for progressively moving said tie-plates along said guideways, and a keeper paralleling said slot and engaging said tie-plates for holding the same in place along said guideways.

3. A furnace for heating the flanges of tie-plate sections of the type including a body plate formed with a transverse flange thereon, said furnace comprising a body of refractory material forming an elongated combustion chamber therein, associated fuel and air blast leads entering the chamber, said body having an elongated opening in the top thereof communicating with said chamber, said opening being relatively narrow as compared with the length of a tie-plate section and spaced parallel guides at the top of the furnace, said elongated opening being adapted to freely receive the flanges of tie-plate sections arranged edge to edge and also adapted to be bridged by the bodies of said sections so related and slidably placed on the top of the furnace body between the guides, said guides being adapted

to co-operate with the ends of such sections and direct said sections, in train, along the top of the furnace, a pusher at one end of the furnace structure adapted to engage the last tie-plate section at the end of a train thereof and to propel said train along the furnace between said guides, and means for preventing the tie-plate sections from buckling in the train thereof under the action of said pusher.

4. A furnace for heating the flanges of tie-plate sections of the type including a body plate formed with a transverse flange thereon, said furnace comprising a body of refractory material forming an elongated combustion chamber therein, associated fuel and air blast leads entering the chamber, said body having an elongated opening in the top thereof communicating with said chamber, said opening being relatively narrow as compared with the length of a tie-plate section and spaced parallel guides at the top of the furnace, said elongated opening being adapted to freely receive the flanges of tie-plate sections arranged edge to edge and also adapted to be bridged by the bodies of said sections so related and slidably placed on the top of the furnace body between the guides, said guides being adapted to co-operate with the ends of such sections and direct said sections, in train, along the top of the furnace, and means for propelling a train of tie-plate sections between said guides.

5. A furnace for heating the flanges of tie-plate sections of the type including a body plate formed with a transverse flange thereon, said furnace comprising a body of refractory material forming an elongated combustion chamber therein, associated fuel and air blast leads entering the chamber, said body having an elongated opening in the top thereof communicating with said chamber, said opening being relatively narrow as compared with the length of a tie-plate section and spaced parallel guides at the top of the furnace, said elongated opening being adapted to freely receive the flanges of tie-plate sections arranged edge to edge and also adapted to be bridged by the bodies of said sections so related and slidably placed on the top of the furnace body between the guides, said guides being adapted to co-operate with the ends of such sections and direct said sections, in train, along the top of the furnace, and means for propelling a train of tie-plate sections between said guides.

6. A furnace for heating the flanges of tie-plate sections of the type including a body plate formed with a transverse flange thereon, said furnace comprising a body of refractory material forming an elongated combustion chamber therein, associated fuel and air blast leads entering the chamber, said body having an elongated opening in the top thereof communicating with said chamber, said opening being relatively narrow as compared with the length of a tie-plate section and spaced parallel guides at the top of the furnace, said elongated opening being adapted to freely receive the flanges of tie-plate sections arranged edge to edge and also adapted to be bridged by the bodies of said sections so related and slidably placed on the top of the furnace body between the guides, said guides being adapted to co-operate with the ends of such sections and direct said sections, in train, along the top of the furnace, and a pusher at one end of the furnace structure adapted to engage the last tie-plate section at the end of a train thereof and to propel said train along the furnace between said guides.

6. A furnace for heating the flanges of tie-plate sections of the type including a body plate formed with a transverse flange thereon, said furnace comprising a body of refractory material forming an elongated combustion chamber therein, associated fuel and air blast leads entering the chamber, said body having an elongated opening in the top thereof communicating with said chamber, said opening being relatively narrow as compared with the length of a tie-plate section, and spaced parallel guides at the top of the furnace, said elongated opening being adapted to freely receive the flanges of tie-plate sections arranged edge to edge and also adapted to be bridged by the bodies of said sections so related and slidably placed on the top of the furnace body between the guides, said guides being adapted to co-operate with the ends of such sections and direct said sections, in train, along the top of the furnace, and means for propelling a train of tie-plate sections between said guides.

7. A furnace for heating the flanges of tie-plate sections of the type including a body plate formed with a transverse flange thereon, said furnace comprising a body of refractory material forming an elongated combustion chamber therein, associated fuel and air blast leads entering the chamber, said body having an elongated opening in the top thereof, communicating with said chamber, said opening being relatively narrow as compared with the length of a tie-plate section and spaced parallel guides at the top of the furnace, said elongated opening being adapted to freely receive the flanges of tie-plate sections arranged edge to edge and also adapted to be bridged by the bodies of said sections so related and slidably placed on the top of the furnace body between the guides, said guides being adapted to co-operate with the ends of such sections and direct said sections, in train, along the top of the furnace, and means for propelling a train of tie-plate sections between said guides.

8. A furnace, as set forth in claim 7, combined in parallelism with a like structure, pushers at the end of the combined structure, one for each unit, each pusher being adapted to engage the last tie-plate section at the end of a train on its respective unit and to propel said train along said unit between its respective guides, and means common to said pushers for synchronously operating the same.

9. A furnace for heating the flanges of tie-plate sections comprising a body portion having a heated chamber and formed with an elongated slot communicating with said chamber, guideways formed along said slot for the reception of a series of flanged tie-plates, said slot being adapted freely to re-

- ceive the flanges of such tie-plates, a trans-
versely disposed rockshaft situated at one
end of said slot, an arm secured to said
rock-shaft terminating in proximity to said
guideways, a link pivoted to said arm and
a pusher-head attached to said link and mov-
able along said guideways for conveying the
tie-plates along said guideways, and means
for rocking said rock-shaft.
10. 10. A furnace for heating the flanges of
tie-plate sections comprising a body portion
having a heated chamber and formed with
an elongated slot communicating with said

chamber, guideways formed along said slot
for the reception of a series of flanged tie-
plates, said slot being adapted freely to re-
ceive the flanges of such tie-plates, trans-
verse supports secured to said guideways at
intervals throughout their length, and a
keeper secured to said supports adapted to
engage said tie-plates for holding the same
in said guideways, and means for conveying
the tie-plates along said guideways.

In testimony whereof, I have signed my
name to this specification.

MELVIN OVESTRUD.

CERTIFICATE OF CORRECTION

Patent No. 1,611,318, granted December 21, 1926.
to MELVIN OVESTRUD.

It is hereby certified that the above mentioned patent was erroneously issued to Twin City **Forge** & Foundry Company, of Stillwater, Minnesota, a Corporation of Minnesota as assignee of the entire interest in said invention, whereas said Patent should have been issued to the inventor, said Ovestrud and Twin City Forge & Foundry Company, said Twin City Forge & **Foundry** Company being assignee of one-half interest only in said invention, as shown by the records of assignments in this office; and that the said Letters Patent should be read with this correction therein that the same may conform to the record of the case in the Patent Office. Signed and sealed this 15th day of February, A. D. 1927.

William A. Kinnan,
Seal. Acting Commissioner of Patents.
